UNITED STATES PATENT OFFICE.

SAMUEL COHEN, OF BROOKLYN, NEW YORK, ASSIGNOR TO GENERAL INSTRUMENT CORPORATION, OF NEW YORK, N. Y., A CORPORATION OF NEW YORK.

VARIABLE CONDENSER.

Application filed November 8, 1924. Serial No. 748,708.

To all whom it may concern:

Be it known that I, SAMUEL COHEN, a citizen of the United States, residing at Brooklyn, county of Kings, and State of New York, have invented a certain new and useful Improvement in Variable Condensers, of which the following is a specification.

My invention relates broadly to electrical apparatus and more particularly to a construction of variable electrical condenser.

One of the objects of my invention is to provide a variable condenser having parts of such mechanical design that they may be readily manufactured in large numbers and assembled to form complete condensers on a quantity production basis.

Another object of my invention is to provide a variable condenser housed within a metallic frame and in which the stator plates are completely insulated from the rotor plates by dielectric material formed of quartz, glass or other hard vitreous materials.

Still another object of my invention is to provide a variable condenser construction in which the frame portions may be stamped from sheet material and arranged to support the stator plates centrally within the frame by means of pedestal insulators secured between each of the frame portions and the stator plates.

Still another object of my invention is to provide an arrangement of parts for a variable condenser construction wherein the stator plates are positively spaced one from another by a spacing member which is in turn supported at each end thereof by a pedestal type of insulator placed in compression by end members which form the frame of the condenser.

Still another object of my invention is to provide means for readily mounting the rotor shaft of a variable condenser between a pair of end plates which form the frame of the condenser.

A still further object of the invention resides in the method of supporting the rotor plates of a condenser by grooving the rotor at a plurality of points spaced one from another into which grooves the plates may be set and secured in position by upsetting opposite sides of the inset portions of the plates.

A still further object of my invention is to provide a ball bearing mounting for one end of the rotor shaft and a screw chuck

journal for the opposite end of the rotor shaft whereby the rotor shaft may be centered between the end frames and revolved to a selected position to move the rotor plates between the stator plates.

A still further object of my invention is to provide a set of stator and rotor plates die pressed upon such a contour that the shape of the plates permits a uniform variation in capacity as the angular position of the rotor plates is changed with respect to the stator plates.

My invention will be more clearly understood by reference to the following specification and the accompanying drawings, in which:

Figure 1 is a plan view of the assembled condenser; Fig. 2 is a side elevation of the condenser illustrating the method of supporting the stator plates on pedestal insulators in compression between the end plates of the condenser; Fig. 3 is a side elevation of the condenser illustrated in Fig. 2; Fig.

4 is a cross sectional view taken through the condenser on line 4—4 of Fig. 3; Fig. 5 is a plan view representing the method of mounting the rotor plates in the rotary shaft; Fig. 6 is a cross sectional view through the rotary shaft showing the method of inserting the rotor plates within the rotary shaft and upsetting opposite sides thereof; Fig. 7 is a cross sectional view showing one type of pedestal insulator which I may employ in supporting the stator plates; Figs. 8 and 9 show the construction of each of the rotor plates and the appearance of the opposite upset edges of the plates; Fig.

10 is a cross sectional view taken through another form of pedestal insulator which I may employ in my condenser construction; Figs. 11, 12 and 13 show the assembly of a modified construction of condenser employing pedestal insulators for the support of the stator plates of the type shown in Fig. 10; Fig. 14 is a detail view illustrating the construction of rotor shaft employed in the condenser construction illustrated in Figs. 11, 12 and 13; and Fig. 15 illustrates the method of mounting the screw chuck journal for the rotor shaft in one of the metallic end plates for the condenser.

My invention provides a construction of variable condenser of high electrical and mechanical efficiency with practically negligible electrical losses. I secure this high ef-

iciency by supporting the stator plates out of contact with the metallic frame of the condenser by means of quartz, glass or other hard vitreous materials. Such material is 5 not subject to drilling or tapping and I have accordingly provided means for interposing this material in the form of pedestals under compression between the spacer members for the stator plates and the metallic end frame 10 of the condenser. The metallic end frames are thereby spaced at a considerable distance from the stator plates out of contact with bodies of opposite electrical charge. I also provide a construction of rotor which enables flat plates to be set into a grooved rotor and opposite edges thereof upset to form a lock with the material of the rotor. I cut the stator plates substantially semi-circular at one edge with lateral projections 15 at each side enabling them to be supported in spacer members located centrally of the condenser frame and between the pedestal insulators under compression. The other edge of the stator plates is cut away enabling 20 the rotor shaft to be operated adjacent the edges of the plates. The edges of the stator plates are then brought out to the ends of the plates upon a substantially straight line. The rotor plates are formed substantially 25 semi-circular at one edge and have opposite edges conforming substantially with the edges of the stator plates. The selected 30 shape of the plates enables a uniform variation in capacity to be obtained for the various angular positions of the rotor plates.

The construction of my variable condenser will be more fully understood by referring to the drawings in detail. Reference characters 1 and 2 designate the end frame plates 35 of the condenser. The frame plate 1 is provided with extending tongues 3, 4, 5 and 6 while the end plate 2 is provided with extending tongues 8, 9, 10 and 11. These 40 tongues provide means by which the plates are joined in frame-like formation by posts 17, 18, 19, 20, and 21. Between the extended tongue portions 3 and 6 I provide a bridge member 12 and correspondingly between the 45 extensions 8 and 11 I provide a bridge member 15. The opposite side of the condenser frame is built up in a similar manner, that is, a bridge member 14 is placed across extensions 4 and 5 while a bridge member 16 is placed across extensions 9 and 10. The 50 bridge members form means for securing the stator plates and insulating pedestals therefor under compression. The stator plates are represented at 34 having substantially semi-circular edges and end portions which 55 extend into grooves 33 in a spacing block 32 as represented more clearly in Figure 7. The spacing block 32 is tapped at each end in order to support a pedestal receiving cap. A cup member 31 is positioned on one end 60 of the spacing member 32 by means of screw 31^a which passes through a washer member 31^b. On the opposite end of the spacing member 32 a cup shaped member 29 is mounted. On the bridge member 14 a cup shaped member 22 is secured by means of screw 24. On the bridge member 16 a cup shaped member 23 is secured held in position by a screw 25. The cup shaped member 23 may be securely positioned upon the bridge 65 16 by means of a screw cooperating with the nut 25. Insulators of pyrex, glass, quartz, ceramic material or other hard vitreous materials are formed in the shape of short cylindrical posts and are interposed 70 between the cup shaped members 22 and 29 and 31 and 23 as represented at 28 and 30. Each cup shaped member is provided with a plurality of longitudinal slots 31^c disposed at a plurality of points about the periphery 75 of the cup shaped members in order to permit the ready insertion of the pedestal insulators. The posts 18 and 19 at one end of the condenser frame are securely drawn together by means of nuts working on screw threads at each end of the posts thereby 80 drawing the end frames 1 and 2 together with the pedestals 28 and 30 in compression. A similar construction is provided at the other end of the condenser frame wherein 85 pedestal insulators 38 and 35 are secured between cup shaped members represented at 36 and 43. Screw devices 26 and 27 position the cup shaped members with respect to the bridges 12 and 15. The spacer block 37 is secured between the cup shaped members 90 100 36 and 43 providing a positive support for the opposite ends of the stator plates. The stator plates are cut away as represented at 65 to secure the shape desired and to enable the rotor to be journaled adjacent the edges of the plates. The rotor comprises a shaft member 52 having an enlarged portion 57 which is grooved at a plurality of points along the length thereof to enable the rotor plates to be set into the rotary shaft. A 105 pair of longitudinal grooves 59 are provided on opposite sides of the rotor 57. The rotor plates 49 are provided with a central extension 60 which may be projected into the groove 58 formed in the rotor 57 and then opposite edges upset as represented at 61 and 62 filling the spaces provided by the longitudinal grooves 59 and locking the rotor plates with relation to the rotor shaft. Each rotor plate is substantially semi-circular at one edge and is provided with a straight edge 64. The other edge is offset 110 and then connected with the semi-circular edge as represented by the straight line 63. This shape in cooperation with the shape of the stator plates 34 enables uniform variation in capacity to be obtained. The shaft 52 is spring pressed at one end by means of 115 a flat spring 68 secured against the end frame portion 2. The other end of the shaft 120 125 130 135

52 is journaled in a bearing formed by a spring chuck 56 secured in the end frame portion 1 by means of nuts 54 and 55. The spring chuck is screw threaded at 53 enabling it to be adjusted longitudinally with respect to the end frame 1 to form an adjustable bearing for the rotor. The adjustment of the chuck 56 is accomplished by loosening nuts 54 and 55 and sliding the 10 chuck longitudinally with respect to the end plate 1. The tongue 66 cooperating with the longitudinally extending groove 75 maintains the chuck 56 in an accurate aligned position with respect to the shoulder 51 of the rotor shaft 52. When a position is reached where the rotor plates 49 are accurately positioned with respect to the stator plates 34, the nuts 54 and 55 are tightened, securing the chuck 56 in position. 15 In Figs. 11, 12 and 13 I have illustrated a modified construction of condenser in which porcelain pedestal insulators 40, 41, 42 and 39 are employed with a large dielectric area for substantially eliminating electrical losses. The rotor shaft 52 in this construction may be provided with a shoulder 51 against which the several stator plates 49 may be positioned and spaced one from another by means of spacer washers and finally locked at the end by means of screw members 48 which engage with the threaded end 47 of the shaft 52. A ball bearing 46 may be provided for the end of the shaft carried in bearing member 44 secured in position by 20 means of nut 45 engaging the screw threaded stem of the member 44 on the opposite side of the frame portion 2. The spring chuck 56 may be readily secured in position with reference to the plate 1 of the condenser frame by means of tongue 66 which projects into a groove 75 in the screw threaded portion 53 of the chuck 56. When the pedestal type of insulator as represented in Figures 11, 12 and 13 is employed as 25 shown in enlarged cross section in Fig. 10, the insulators 40 may be interiorly threaded as represented at 40^a to enable the screw threaded end 25^b of the nut 25 to be screwed within the screw threads 40^a to securely position the pedestal in position. The entire condenser may be mounted relative to a panel or other surface by means of screws and cooperating bushings 67, 69 and 70. 30 It will be observed that the condenser construction which I have described may be readily manufactured and assembled and that the pedestal insulators insure a dielectric of high quality. 35 While I have described my invention in certain particular embodiments I desire that it be understood that modifications may be made and that I intend no limitations upon the invention other than those imposed by the scope of the appended claims.

What I claim and desire to secure by Letters Patent of the United States is as follows:—

1. A variable condenser construction comprising in combination a pair of end plate portions, a plurality of stator plates positioned between said end plate portions, spacer members at opposite ends of said plates for positively spacing each of said plates one from another and a plurality of pedestal insulators interposed between said end plates and said spacer members for supporting said stator plates apart from said end plate portions.

2. A variable condenser construction comprising in combination a pair of end plates, a plurality of posts interconnecting said end plates forming a frame, a plurality of stator plates carried within said frame, a pair of spacer members at opposite ends of said plates positively spacing said plates apart and a plurality of insulated posts interposed between said spacer members and said end plates.

3. A variable condenser construction comprising in combination a pair of flat end plate members, a plurality of stator plates, a pair of spacer members at opposite ends of said plates operating to positively space said plates apart and a plurality of cylindrical insulators interposed between said spacer members and each of said plates for centrally positioning said spacer members between said end plates.

4. A variable condenser construction comprising in combination a pair of substantially flat end plates, a pair of arms extending from each of said plates, a bridge member interconnecting each of said pairs of arms, a plurality of stator plates, a spacer block positioned at opposite ends of said plates for positively spacing said plates apart and insulating means interposed between opposite ends of said spacer blocks and said bridge members and maintained under compression for centrally locating said stator plates intermediate said end plates.

5. A variable condenser construction comprising in combination a frame, a plurality of stator plates centrally located within said frame, a spacer block at opposite ends of said stator plates and insulation means interposed between said spacer blocks and said condenser frame and maintained under compression for securing said stator plates in position intermediate said end plates.

6. A variable condenser construction comprising in combination a frame, a plurality of stator plates centrally located within said frame, a spacer block at opposite ends of said stator plates and a pair of pedestal insulators interposed between opposite ends

of each of said spacer blocks and said end plates for securing said stator plates intermediate said end plates.

7. A variable condenser construction comprising in combination a frame, a plurality of stator plates centrally located within said frame, a spacer block at opposite ends of said stator plates and short cylindrical insulators interposed between opposite ends of 10 said spacer blocks and said end plates for securing said stator plates intermediate said end plates.

8. A variable condenser construction comprising in combination a frame, a plurality 15 of stator plates centrally located within said frame, a spacer block at opposite ends of said stator plates and a pair of quartz insulators interposed between opposite ends of each of said spacer blocks and said end 20 plates for positioning said stator plates intermediate said end plates, and means for maintaining said quartz insulators and spacer blocks under compression between said end plates.

25 9. A variable condenser construction comprising in combination a frame, a plurality of stator plates centrally located within said frame, a spacer block at opposite ends of said stator plates, a vitreous post interposed 30 between said spacer blocks and said condenser frame and maintained under compression for securing said stator plates in position intermediate said end plates and means binding said end plates together.

35 10. A variable condenser construction comprising in combination a pair of substantially flat end plates, a pair of arms extending from each of said plates, a bridge member interconnecting each of said pairs 40 of arms, a plurality of stator plates, a spacer block positioned at opposite ends of said plates for positively spacing said plates apart, a cup shaped device carried intermediate the length of said bridge members, 45 a corresponding cup shaped device carried on each end of said spacer blocks and insulating means interposed between said cup

shaped devices and maintained under compression for centrally locating said stator plates intermediate said end plates.

60

11. A variable condenser construction comprising in combination a pair of end plates, a plurality of posts interconnecting said end plates forming a frame, a plurality of stator plates carried within said frame, a pair of spacer members at opposite ends of said plates positively spacing said plates apart, a resilient cup shaped device positioned adjacent opposite ends of said end plates, a similar resilient cup shaped device positioned on opposite ends of said spacer members and insulated posts interposed between each of said cup shaped devices for substantially insulating said stator plates from said end plates.

65

12. A rotor for a variable condenser comprising a rotary shaft, a bearing for opposite ends of said shaft, an enlarged longitudinal section forming part of said shaft, said section having a plurality of lateral grooves cut substantially through one half the diameter thereof, a pair of longitudinal grooves connecting the opposite sides of said plurality of lateral grooves, a plurality of rotor plates adapted to be secured upon 70 said rotary shaft, said rotor plates having an intermediate portion arranged to extend into said lateral grooves with the edge material of said portion adapted to be upset and filled within the space of said longitudinal grooves for locking said plates with respect to said shaft.

75

13. In a variable condenser construction a frame comprising a pair of end plates, a rotor, bearings for said rotor comprising a ball pivot carried by one of said end plates and a spring collet chuck carried by the opposite end plate and having means for adjusting said chuck longitudinally on the axis of said shaft whereby said rotor plates 80 may be centrally positioned between said end plates.
